UNITED STATES PATENT OFFICE.

SEVERN WINBERG, OF GALESBURG, ILLINOIS.

SPIRIT-LEVEL AND PLUMB.

SPECIFICATION forming part of Letters Patent No. 761,279, dated May 31, 1904.

Application filed December 7, 1903. Serial No. 184,152. (No model.)

To all whom it may concern:

Be it known that I, SEVERN WINBERG, a citizen of the United States, residing at Galesburg, in the county of Knox and State of Illinois, 5 have invented certain new and useful Improvements in Spirit-Levels and Plumbs, of which the following is a specification.

My present invention relates to spirit-levels and plumbs of the general type or class known 10 as "builders' levels and plumbs," and particularly to that specific type or class of the same known as "gravity levels and plumbs."

It further relates to an improvement on my Patent No. 710,388, granted September 30, 15 1902, on spirit-level and plumb.

The objects of my present invention are, primarily, to overcome difficulties with which I have met in the use and practice of my aforesaid patented invention and especially in the 20 adjustment thereof.

With this and other objects in view the invention consists in the novel construction and combination of parts, all as hereinafter described, and pointed out in the appended 25 claims.

In the accompanying drawings, which are made a part of this specification, similar letters of reference refer to like parts in the different figures thereof, and in which—

30 Figure 1 is a plan elevation showing the plumb and also showing the level with its casting removed; Fig. 2, a detail elevation; Fig. 3, a plan section on the line 3 3 in Fig. 4; Fig. 4, an end elevation; Fig. 5, a section showing 35 covering-latch; Fig. 6, a sectional view of parts; Fig. 7, the blank from which the level-glass-containing cylinder is formed; Fig. 8, the blank rolled up into shape, partly broken away; Fig. 9, the cylinder-cap.

40 As hereinbefore stated, I have met with faults and difficulties in the use and practice of the device shown, described, and claimed in the use of my aforesaid patent. One and perhaps the chief of these faults was in the 45 adjustment of the level tube or glass and its containing-cylinder, owing to the following: When used when and where there is much moisture, the stock is liable to become warped by expansion or contraction, thereby throwing 50 the level-glass and its containing-cylinder

out of plumb or adjustment. In such case it was necessary in my prior device to remove two parts in order to gain access to the adjusting-screw. It was also necessary to have a screw-driver or some other tool by which the parts might be adjusted. In my present invention it is unnecessary to remove any part, thus saving a great deal of time; neither is any tool needed to make the adjustment, as will be hereinafter described.

For the purposes of this invention it will be unnecessary to describe any more thereof than those parts which relate particularly thereto.

I represents a level-stock; D, a frame in 65 an opening I' therein; C, an adjusting-wheel threaded on for the purpose of adjusting, limiting, and regulating the movement of the plate A; A', a level-tube-containing cylinder or capsule having an opening A' and having 70 studs or journal E E', integral therewith, projecting from its outer end and at or near its periphery and A² a level glass or tube within said cylinder or capsule. The plate A is seated in slots or openings D' in the frame 75 internally thereof, and its threaded end projects through one of said openings, as shown best at Figs. 4 and 6. The stud or journal E is seated in a bearing A⁴, Fig. 6, in the plate A near its mid-length, and the stud or journal E' is seated in a suitable bearing in the distal end of the frame.

D² is a disk or plate fixed to the stock A by screws A⁶ to partly cover the opening I' and hold or retain the frame in place therein and 85 has an opening F', through which access may be had to the roughened, milled, or notched periphery of the wheel C, and also has a latch or cover F hinged or pivoted thereto, which latch may have a detent on its under 90 side to engage with the slot F' and prevent accidental displacement of the adjusting-wheel. The latch further serves to prevent dust or dirt entering through the slot and clogging or interfering with the operation of 95 the device. Another disk or retaining plate (not shown) is secured to the stock on its reverse side also for holding or retaining the frame therein. The wheel is held from side- 100 wise or lateral movement partly by a slot D³

in the frame, partly by a slot D⁴ in the level-stock, and partly by a slot F' in the disk D². Thus held the wheel C acts as and performs the functions of a nut into which the end of 5 the plate A is threaded.

When it is desired to adjust the stud or journal E, and thereby the proximal end of the cylinder and level-glass, the operator by 10 revolving the wheel C with his thumb or finger will cause the plate, and thereby the last aforesaid parts, to be drawn or thrust in one direction, and by reversing the direction of revolution of the wheel the direction of movement of said parts will be reversed and a 15 ready and positive adjustment of said parts thus effected.

G is a blank from which the cylinder or capsule is partially formed. After it is rolled up into cylindrical form and its edges soldered 20 together the level-tube is placed therein and a disk or cap H is loosely soldered in either end of the cylinder. Should it be desirable to remove one of these caps, a knife-blade or other sharp-pointed instrument may be inserted 25 at its periphery and pressed outward, when the cap will fall out.

Without limiting myself to the details of construction and arrangement shown, I claim—

30 1. In a spirit-level, and in combination, a level-stock having an opening therein, a frame resting therein, a cylinder within said frame, journals at the ends of said cylinder, a level-glass contained within said cylinder, slots in the frame, an adjustable plate carried by the frame to move in said slots, said plate having one of its ends threaded and having a bearing in which one of said journals is seated, a bearing in the distal end of the frame, in 35 which the other of said journals is seated, and a wheel threaded on the threaded end of the plate, substantially as described and for the purpose specified.

2. In a spirit-level and in combination, a 45 level-stock having an opening therein, a frame within said opening, a level-tube-containing cylinder, journals integral with said cylinder and at the ends and at or near the periphery

thereof, a level-glass within the cylinder, slots in the frame and an adjusting-plate seated in 50 said slots, one end of the adjusting-plate being threaded, a bearing in said plate, in which one of the journals is seated, a bearing in the frame, in which the other of said journals is seated, another slot in the frame, a slot in the 55 level-stock, a wheel resting in and held from lateral displacement by said slots, said wheel threaded on the threaded end of the plate for adjusting it and thereby the proximal end of the cylinder in higher or lower positions, sub- 60 stantially as described.

3. In a level, the combination of a stock I, a frame D, a cylinder having journals E, E', a level-glass within said cylinder, slots D' in 65 said frame, a plate A seated in said slots, one end of said plate being threaded and extended beyond the frame, a bearing in said plate, a wheel C threaded onto the extended end of the plate for the purpose described, a bearing in the frame, a retaining-disk, a slot there- 70 in, and a latch thereon, all substantially as described and for the purpose specified.

4. In a level and in combination, a frame, an adjustable plate partly within said frame and having a threaded end, slots in said frame 75 in which the plate is carried, a wheel partly within said frame, said wheel being threaded onto the threaded end of the plate, a bearing in the frame, a bearing in the plate, and a level-tube-containing cylinder seated in said 80 bearings, substantially as described.

5. In a spirit-level, and in combination, a stock, a cylinder containing a level-tube, an adjustable plate having a bearing in which one end of said cylinder is journaled, one end 85 of the plate being threaded, a wheel in threaded engagement with the adjustable plate, a frame, a bearing in said frame, in which the other end of the cylinder is journaled, and plates for retaining said parts in place within 90 the stock, substantially as described.

SEVERN WINBERG.
